H. F. Everts

UNITED STATES PATENT OFFICE.

HARRY E. LONG, OF LONDON, ONTARIO, CANADA.

ELECTRICAL CONNECTOR.

SPECIFICATION forming part of Letters Patent No. 278,346, dated May 29, 1883.

Application filed November 6, 1882. (No model.)

To all whom it may concern:

Be it known that I, HARRY E. LONG, of London, in the county of Middlesex and Province of Ontario, Canada, have invented a new and useful Improvement in Electrical Connectors, of which the following is a full, clear, and exact description, reference being had to the accompanying drawings, which form part of this specification.

10 My invention relates to an improvement in electrical connectors, more especially designed to be used for connecting in a closed circuit the cars of a railway-train and the locomotive drawing them, having a battery and an electric bell in circuit, so that if the circuit be broken at any point in the train, either by design or by accident, the locomotive-driver will be signaled through the bell to stop.

15 My invention consists in the peculiar construction of a plug and a spring-socket, of each of which one is to be attached to the flexible wires or cables running through each car, so that they can be quickly engaged with corresponding devices in adjoining cars to complete the circuit through the train.

20 Figure 1 is a perspective view of my connectors detached or uncoupled. Fig. 2 is a horizontal section of the same at *xx* in Fig. 1. Fig. 3 is a similar section of the same coupled, to show why they will not uncouple in the sagging of the cable. Fig. 4 is a vertical longitudinal section at *yy*.

25 In the drawings, *A* represents the male plug of my connector, having at one end a socket, *a*, to receive the terminal of a wire or cable intersected by a tapped hole, in which is inserted a binding-screw, *a'*, to secure them together. The other end of the part *A* terminates in an oval or elongated head, *A'*, having 30 a contracted neck, as shown at *c'*.

B is the socket part, having a hole, *b*, in the

base to receive the terminal, which is secured thereto by a binding-screw, *b'*. The part *B* is composed of two parallel plates, with an interposed block, *B'*, at one end, which forms the 45 base, to which the terminal is coupled.

50 *C C* are two leaf-springs, one end of each of which is secured to the block *B'* in such a manner that their free ends may play between the stationary plates. The free end of each is formed with a curved or convex boss, *c*, on the 55 inside, adapted to enter and engage with the neck *c'* when the head *A'* is forced between them.

55 The form of the parts is such that they will disengage under a smart pull in a direct line, but will not separate from their own weight when sagging, as is shown in Fig. 3. They can be quickly coupled by pushing the head *A'* between the springs *C C* in a right line. Preferably they should be made of steel, and may be 60 protected by covering with a non-conductor, if desired.

65 What I claim as my invention is—

An electric connector for train-telegraphs, 65 consisting of a plug having an elongated head and contracted neck, and a socket part having its top and bottom formed of stationary plates and its sides of leaf-springs, the plates and springs being secured to an interposing 70 end block, as shown, and the springs being protected by the stationary plates, and provided at their free ends with a convex boss adapted to enter and engage the contracted neck of the plug when the latter is forced into 75 the socket part, as and for the purposes set forth.

HARRY E. LONG.
